UNITED STATES PATENT OFFICE.

PETER BEAHM, OF ALTOONA, PENNSYLVANIA.

AUTOMATIC CONNECTOR FOR TRAIN-PIPES.

No. 872,707.

Specification of Letters Patent.

Patented Dec. 3, 1907.

Application filed June 29, 1907. Serial No. 381,526.

To all whom it may concern:

Be it known that I, PETER BEAHM, a citizen of the United States, residing at Altoona, in the county of Blair and State of Pennsylvania, have invented certain new and useful Improvements in Automatic Connectors for Train-Pipes, of which the following is a specification, reference being had therein to the accompanying drawing.

10 My present invention relates to improvements in automatic connectors for train pipes, and has special reference to a new and improved coupler for air-brake, signal and steam pipes upon passenger trains, and for 15 air-brake pipes upon freight trains.

The main object of my invention is the provision of a device of this character which is connected to and supported entirely by the car coupler, and so constructed as to 20 always be below and in line with said coupler, so that when the coupling is being made, the meeting or co-acting members of each 25 coupler will engage simultaneously, and after the car coupler is fast, the pipe couplers will remain engaged until the car couplers again 30 part.

Another object of my invention, is the provision of a coupler of this class, which can be quickly applied to any car coupler now in use, 35 and by reason of its simple construction is no great burden upon the coupler.

Another object of my invention is the provision of an automatic coupler, which will not necessitate the full equipment of a train 40 with the same coupler, as this coupler is designed with means whereby the general forms of couplers now in use can be attached to my automatic coupler, thus making my invention very practical and ready for immediate use.

To this end, my coupler consists of a frame which is adjustably supported from the car coupler by connection with the knuckle pin and an adjustably alining device, the said 45 frame having mounted therein a sliding carriage which is normally held projected by a spring. The carriage carries the pipe couplers, so that they normally project beyond the outer end of the car coupler, so that when 50 the adjacent ends of the cars come together the pipe couplers will contact each other slightly ahead of the car couplers, which after they are coupled, are held together by the spring-actuated carriages which are 55 forced toward each other, and thus the pipe couplings are held in close engagement dur-

ing the coupling of the cars, and do not become uncoupled until the car couplers are separated a certain distance, the frame being provided with limiting means whereby the 60 projection of the carriage is stayed. Where my automatic coupler is mounted upon passenger cars, the carriage carries three alined couplings, that is one for the air-brake, one for the signal pipe and one for the steam 65 heating pipe, whereas when mounted upon a freight car, the carriage carries only the air-brake pipe coupling.

To more clearly illustrate the preferred form of my invention, attention is invited to 70 the accompanying drawings, in which:

Figure 1 is a side elevation of two complete car and automatic couplers just before the operation of "coupling". Fig. 2 is a similar view of the same "coupled", one of 75 the automatic couplers being in section. Fig. 3 is a view showing the forward end view of one coupler and the rear end view of the other, the steam-heating pipe connection of one, being in section. Fig. 4 is a top plan 80 view of two "coupled" couplers, one of them being in section. Fig. 5 is a top plan view of one of the couplers in the position it assumes when connected with an ordinary coupler, and Fig. 6 is a side elevation thereof. 85

Referring to the drawings:—the letter A designates one car coupler and B the other or co-acting car coupler, while C and D, designate the two similarly constructed co-acting automatic couplers, constructed according to and embodying my invention.

Each car coupler is provided with an elongated knuckle pin 1, upon whose lower end is mounted a sleeve 2, held from sliding thereoff by means of the cotter pin 3. This sleeve 95 2 carries the substantially right-angled arm 4, whose upper end is slotted as at 5, and has adjustably mounted therein the double-ended clamp 6, whose single claw end 7, is adapted to the forward end 8, of the car coupler, 100 while its T-shaped end 9, is adapted to engage the body of the coupler as at 10, and thus by means of the adjusting and clamping screw 11, securely hold the sleeve 2 against turning, so that the automatic coupler is always in alinement with the car coupler. 105

Projecting rearwardly from the sleeve 2, is a short arm 12, which is provided with the pair of ratchet plates, 13, separated by the slots 14, for the reception of the adjusting 110 and clamping bolts 15, which pass through the said slots and the slots 16, of the pair of

ratchet plates 17, carried by the upper forward end 18 of the frame 19. By this adjusting means the relative height at which the frame 19 is supported by the car coupler 5 is maintained.

The frame 19, consists of the two parallel slotted members 20 and 21, which terminate in the reduced yoke 22, in which is mounted the coiled spring 23, seated upon the boss 24. 10 Slidably mounted within the opposed recesses 25, of the members 20 and 21, is the vertical cross-bar or frame 26, which carries the winged boss 27, which is received by the outer end of the coiled spring, said boss having upon its outer face, the knobbed stem 28, which is at all times contained in and in engagement with the substantially spherical socket 29. This socket 29 is carried by a stem 30, which is formed integral with the 15 coupler-carrying frame or carriage 31, which is provided with the oppositely disposed cylindrical guiding stems 32 and 33, which fit in and slide within the slots of the members 20 and 21, and form a pivot whereby the carriage may be swung to either allow the coupler to be used automatically or manually, as will presently appear. From this description it will be seen that the coiled spring normally projects the carriage, so that the train 20 signal pipe coupler 34, the central air-brake coupler 35, and the steam heating pipe coupler 36 will normally project beyond the farthest projection of the car coupler, this being clearly illustrated in Fig. 1.

35 Formed integrally upon the forward portion of the stem 33, which by the way is hollow, is a lug 37, which is provided with a seat 38, to engage the stem or projection 39, upon the forward end of the lower member 21. 40 By this means the various couplers are limited in their forward movement, and to prevent the carriage from turning and to hold it in the desired relative position, I provide this seat 38 and stem 39, when the coupler is 45 automatic, or I swing the carriage, as illustrated in Figs. 5 and 6, where convoluted plate 40, has its seat 41 in engagement with the stem 39, and the couplers are turned to one side and held there by the action of the 50 coiled spring and said seating devices so that the ordinary couplers may be conveniently secured in place. The plate 40 is cast integral with and upon the forward portion of the carriage 31.

55 The carriage is provided with three obliquely arranged ports 42, 43 and 44, to which is connected the train signal pipe 45, the air-brake pipe 46 and the steam heating pipe 47, respectively, said pipes being connected from below the carriage. Each one of these connections consist as clearly illustrated in section, Fig. 2, of a hollow ball or head 48, provided with the series of ports 49, said head being held against upward displacement by means of the plug 50, which

also holds the curved lower portion 51 of the head upon the lead washer or seat 52, mounted within the lower portion of the enlarged end of each port 42, 43 or 44. By this means it will be seen that the stem 53 carried by the head 48, is placed within the carriage after the washer has been placed within the port and the plug 50 is disconnected. By this means I provide a ball and socket connection for each train pipe, and the stems 75 carried by each head 48 may be connected to the various train pipes by means of an universal coupling.

The central air brake coupler 35, is in communication with the port 43, through the 80 central channel or duct 54 of the carriage, while the train signal pipe coupler 34 is in communication with the port 42, through the medium of the curved duct 55, which extends upwardly as at 55', while the steam pipe coupler 36, is in communication with the port 44, through the medium of the oppositely curved channel or duct 56. The ports 42, 43 and 44 are preferably made in one casting 57, and the mouths thereof are 90 in the same vertical line, and are directly below and in line with the car coupler when the stem 39 and seat 38 are in engagement, and in the mouth of each port is mounted the soft metal coupling 58, each of which is preferably made of lead, and is forced in so as to fit snugly within the mouth of each port. The outer faces 59, of each coupler is in the same plane, so that as the couplers come together each coupling 58, of the respective 100 coupling members C and D, will contact simultaneously, and as they project beyond the ends of the car couplers A and B, they are seated before the car couplers finally engage. The coiled springs will at all times 105 hold the lead couplers together, and as the coupling members are so attached to the car couplers as to insure proper meeting, a practical automatic coupler is produced. Should, however, the car coupler A be 110 slightly to one side of the coupler B, and possibly a fraction lower, I form upon one side of the carriage the rectangular funnel guide 60, which terminates in the cylindrical seating opening or sleeve 61, for the reception of the pointed cylindrical pin 62, carried by the other coupling member upon the same side as the guide 60. In other words, each carriage is provided with a guide 60 and a seating pin 62, and by means of the peculiar construction of the inclined walls of the guide, the pin no matter at what point it may contact either wall will be guided toward and into the sleeve 61, at which point the couplers engage, and are held in engagement during the period of engagement of the car couplers.

115 As illustrated in Figs. 5 and 6, the couplers A, are adjusted to be engaged by the ordinary couplers, and by this means, the great 120

objection to the various automatic couplers heretofore invented are overcome, as my automatic coupler is not necessarily applied to all the cars throughout a train, but may 5 be effectually connected to the ordinary couplers now in use, and not necessitate the immediate discarding of the present equipment.

In order that the ordinary couplers (not 10 shown) may be attached to the train signal and air brake couplers, the carriage is turned so that the stem 39 engages the seat 41 of the convoluted plate 40, at which point the said 15 couplers are moved to one side so as to be readily reached by the party manipulating the couplers, and are held in such position by the coiled spring, which exerts the proper forward tension to accomplish this result. Each carriage is provided with the dove-tailed projection or lug 63, which fits in the hooked lug 64 of the ordinary coupler 65, while the hooked lug 66, after the lug 63 has 20 engaged the hooked lug 64, of the ordinary coupler, and the coupler is turned, receives 25 the lug 67, of the ordinary coupler, and by the said turning action, the ordinary coupler is locked to the proper coupler of the carriage. That is the lugs of the ordinary coupler are the same shape as those of the 30 automatic coupler 58, whereby the two are locked by simply placing their faces together with the lugs out of line; and then turning the ordinary coupler so as to bring a straight lug in engagement with a hooked lug, this 35 being of general construction, and as now used.

The steam heating pipe is connected to the automatic coupler through the medium of the short pipe 68, clearly illustrated in Figs. 40 3 and 4, which is connected to the stem 69, which is inserted through the coupling 70, before the plug 71 is inserted. The upper end of the stem is provided with a spherical head 72, having a series of ports 73, which 45 allow communication from the long pipe 74 to the coupler. Mounted within the coupling 70, is a lead washer or valve seat 75, which with the lower portion of the head 72 provides a recess 76, which is filled with a 50 lubricant, for the joint, and as the opening 77 of the coupling is provided with the downwardly and outwardly inclined walls, the pipe 74 can rock in all directions without 55 affecting the working of the device. The upper end of the pipe 74 is connected to the 60 cock 78, carried by the car, through the medium of the similarly constructed ball and socket coupling 79, and it will be seen that any rocking motion of the car is provided for, and rubber hose is dispensed with.

What I claim, as new, is:—

1. In combination with a car coupler and the train pipes of a train, of an automatic coupler for the pipes pivotally connected to 65 the knuckle pin of the car coupler and having

adjustable means to hold the pipe couplings relatively to the car coupler.

2. In combination with a car coupler and the train pipes of a train, of an automatic coupler for said pipes, consisting of a frame, 70 means for connecting the same to the coupler, adjustable means for holding the same in a relative position to the car coupler, an adjustable means for holding the coupling members of each coupler in horizontal co- 75 relation, and spring actuated couplers for the pipes carried by the frame.

3. In combination with a car coupler and the train pipes of a train, of an automatic coupler for said pipes, consisting of a 80 frame, means for connecting the frame to the knuckle pin of the car coupler, adjustable means for holding the same in a relative position to the car coupler, a carriage slidably and pivotally mounted within said frame, 85 pipe couplers carried by said frame and in engagement with said train pipes, and means for projecting the carriage forward and exerting a tension in such direction.

4. In an automatic connector for train 90 pipes, the combination of a frame, a carriage slidably and pivotally mounted in said frame, and means for projecting the carriage and holding the connector either directly forward or to one side, for the purpose set 95 forth.

5. In combination with a car coupler and the train pipes of a train, of an automatic coupler for the pipes, consisting of a frame supported by the car coupler, a carriage slid- 100 ingly and pivotally mounted and capable of transverse tilting movement in said frame, 105 couplers carried by said carriage, and means for projecting the carriage and holding the coupling either in or out of line with the car 110 coupler, for the purpose set forth.

6. In combination with a car coupler and the train pipes of a train, of an automatic coupler for the pipes, consisting of a frame, 110 means for attaching the frame to the car 115 coupler, a carriage slidably and pivotally mounted and capable of transverse tilting movement in said carriage, couplers carried by the carriage, means to limit the forward and inclined position of the carriage and also to lock it either in a straight or inclined position, and spring actuated means for holding the carriage in the desired position.

7. In combination with a car coupler and the train pipes of a train, of an automatic 120 coupler supported from the knuckle pin of the car coupler, and an adjustable clamping device engaging the car coupler for holding the automatic coupler in relative alinement with the car coupler.

8. In combination with a car coupler and the train pipes of a train, of an automatic coupler for the pipes, means connecting the automatic coupler to the knuckle pin of the car coupler, and an adjustable means carried 130

- by the automatic coupler and in detachable engagement with the body of the car coupler whereby the couplers of the automatic coupler retain the same relative position with the car coupler.
9. In an automatic connector for train pipes, the combination of a frame, means for securing the same to the car coupler and the pipes, a carriage carrying the couplings for the pipes mounted in the carriage so that the carriage is free to slide backward and forward within the frame and be capable of tilting so as to present the couplers either in front or to one side of the frame, a spring mounted in the frame and exerting a tension toward the carriage, and a connection between the frame and spring whereby the spring holds the carriage forward and in either a straight or inclined position.
10. In combination with a car coupler having a knuckle pin and an automatic connector for the train pipe, of means for supporting the connection from the coupler consisting of a member connected to the lower end of the pin, a clamp extending forwardly and engaging the body of the coupler to prevent turning of the connector, and a vertically adjustable connection between the connecting means and the automatic connector.
11. The combination with a car coupler, of an automatic connector supported and carried by said coupler, and consisting of a frame, a carriage pivotally and slidably carried in said frame, a spring for normally holding the carriage forward, couplers carried by the carriage, and means carried by each coupler, whereby said couplers may be manually coupled to an ordinary coupler.
12. In combination with a car coupler, of an automatic connector for the train pipes supported and carried by the car coupler, and consisting of a frame, a carriage pivotally and slidably mounted in said frame, a socketed knob carried upon the rear of the carriage, a spring mounted in the frame and carrying a knob to fit in said socket and exert a tension upon the carriage to hold it forward and either in or out of line with the car coupler, and couplers carried by the carriage.
13. In combination with a car coupler, of an automatic connector for the train pipes supported and carried by the car coupler, and consisting of a frame, a carriage pivotally and slidably mounted in said frame, a socketed knob carried upon the rear of the carriage, a spring mounted in the frame and carrying a knob to fit in said socket and exert a tension upon the carriage to hold it forward and either in or out of line with the car coupler, a plurality of vertically arranged couplers carried in the forward end of the carriage, and means carried by each coupler whereby said couplers may be manually coupled to an ordinary coupler.
14. In combination with a car coupler, of an automatic connector for train pipes supported and carried by the car coupler, and consisting of a frame, a carriage provided with a series of channels therethrough and pivotally and slidably mounted in said frame, means for connecting said channels with the train pipes, means carried at the forward end of the channels for connecting the train pipes of each car together, a spring mounted in the frame and in engagement with the carriage to hold the carriage forward and in or out of line with the car coupler, and a connection between said carriage and spring consisting of a ball and socket joint.

In testimony whereof I affix my signature in presence of two witnesses.
